UNITED STATES PATENT OFFICE.

URBAN GÜTLING, OF WÜRZBURG, GERMANY.

BINDING ATTACHMENT FOR SEWING-MACHINES.

SPECIFICATION forming part of Letters Patent No. 578,561, dated March 9, 1897.

Application filed June 14, 1895. Serial No. 552,860. (No model.)

To all whom it may concern:

Be it known that I, URBAN GÜTLING, of Würzburg, Bavaria, in the German Empire, have invented an Improved Machine for Edging or Binding Trousers, of which the following is a specification, reference being had therein to the accompanying drawings.

This invention relates to an improved machine for providing trousers with braids or borders, its object being materially to simplify these operations and thereby to enable them to be more neatly and rapidly performed than it has been possible to do before.

The device for applying edging or borders to pantaloons forming the subject-matter of this invention has the advantage over devices used for the same purpose heretofore that the edging-strip is guided solely by a smooth channel having space only sufficient for the passage of the two layers of the folded edging-strip, thus dispensing with a separate guide or spring, whereby the objectionable and customary holding or retarding of the strip is avoided and the work can be done quicker and more uniformly than has heretofore been possible.

In the accompanying drawings, forming a part of this specification, and in which like letters of reference indicate like parts in all the views, Figure 1 is a plan view of the device with the cover closed; Fig. 2, the same with the cover opened. Fig. 3 is a front view of Fig. 2 with the braiding-strip inserted. Figs. 3^a and 3^b are details. Fig. 4 shows the device with the cover closed.

A plate *a* is secured to a sewing-machine in such a manner that the machine-needle in descending passes through an aperture *a'*, provided in the said plate. On the plate *a* there is secured a box or case *b*, having a flat lateral extension or projecting plate *c*. By raising the lid *d* of the case *b* a channel or passage *e* is uncovered. The width and depth are so proportioned that when the said lid is closed the strip of material *f*, which is to form the border, will just fit the said passage *e* when folded once or doubled up, Fig. 1.

As is well known, the usual process in edging trousers is to fold up the band of material *f*, which is to form the edge or border, as shown in Fig. 3^a, and to connect it with the two pieces *f'* and *f''* of the material, (also

folded up,) the wrong side of the material being turned outward both at *f'* and *f''* when the two superposed pieces of material have 55 been stitched to the band or border and to each other, as illustrated in Fig. 3^a they are turned over so as to assume the shape or position indicated in Fig. 3^b when the edging is completed. In order to accomplish this in 60 accordance with the present invention, the lid *d* is opened and the strip or band *f* is so inserted that it takes up the position in which it is represented in Fig. 1, with the back of the fold to the left. The two pieces of 65 material *f'* *f''* are passed, respectively, over and under a projecting plate or shoulder *g*, formed on the case or box, and are retained in position and guided by the left longitudinal side *b'* of the said box. The material, 70 which is moved along by the cloth-feeder in the usual way, is stitched to the band or border at the point *a'*. Now it will be understood that the said band is so guided by the guide-groove *e* that it moves into required 75 situation of its own accord without requiring any assistance from the operator's hand, in which position it may be readily joined to the two pieces *f'* *f''* of the cloth. The main point therefore is that the two pieces *f'* *f''* 80 are in close contact with the side *b'* of the box, which insures careful attention, and in itself is a sufficient guarantee of rapid and easy operation.

According to the position which the box *b* 85 occupies in relation to the stitching aperture or eye *a'* the width of the border may be varied, the stitch itself changing accordingly its position in relation to the material, so that a piece of the braid *f*, of greater or less 90 width, as the case may be, becomes visible when the edging or braiding is completed.

In order to facilitate the adjustment of the box *b*, its projecting plate *c* is provided with slots, through which set-screws *K* are passed. 95 Upon loosening these screws the said box may be shifted laterally and one longitudinal edge of the plate *c* (on the right) may be brought into coincidence with one of the indicating lines or marks *l* on the plate *a*. The 100 adjustability of the box is an important feature, especially for purposes of army tailoring or military equipment. To insure a perfect closing of the lid *d*, while enabling it at

the same time to be readily opened if need be, a closing or locking lever i is linked or pivoted onto a screw h , inserted into the said lid, one end of which lever is subjected to 5 the action of a spring i^2 , and both its ends being formed with hooks adapted to embrace or surround each a pin i' on the box when the lid is turned down. In order to open the lid, it is only necessary to shift the lever 10 end i sidewise, overcoming the resistance of the spring i^2 in the act, when the lid may be opened without any difficulty.

I claim—

In a binding-machine, the combination of

the plate a having needle-opening a' , the box 15 b mounted upon the plate a and having a guiding edge b' and a braid-channel e , the projecting shoulder g secured to the box b , a lid d closing the channel e , and a spring-lever locking the lid in position, substantially as 20 set forth.

In witness whereof I have hereunto set my hand in presence of two witnesses.

URBAN GUTLING.
